FLAG AND FLAGPOLE HOLDER

William F. Hogan, Wildwood, N. J.

Application October 18, 1937, Serial No. 169,584

5 Claims. (Cl. 248—42)

My invention relates to a new and useful flag and flagpole holder of the general type disclosed in my prior Patents Nos. 1,788,157 and 1,893,585, the present invention being directed to various improvements in structure and function over my prior patents referred to as well as the prior art.

My invention more particularly relates to a flag and flagpole holder adapted for the support of a plurality of flags in variously adjustable positions with respect to each other whether such flags be of the type mounted on a flagpole, or whether they be of the "pull-down" type, that is, the type of flag which is secured to a horizontal support along one edge thereof and is allowed to hang down or to be draped about a light standard or telephone support or similar support.

My invention further relates to various other novel features of construction and advantage residing in single structural features or in combinations thereof, as more fully hereinafter set forth in the following specification and the accompanying drawings in which:

Fig. 1 represents a plan view of a flag and flagpole holder of the type that may be applied to a light standard or telephone pole, the same being shown detached.

Fig. 2 represents a left hand side elevation of Fig. 1.

Fig. 3 represents a section on line 3—3 of Fig. 2.

Fig. 4 represents a fragmentary section, on an enlarged scale, on line 4—4 of Fig. 2.

Fig. 5 is a fragmentary front elevation of the pull-down flag support shown at the lower portion of Fig. 1 illustrating a manner of angular adjustment of the pull-down support with respect to a flag holder associated with said support.

Fig. 6 represents a front elevation of a flag holder adapted to be associated with the pull-down support illustrated in Fig. 5, and also showing a manner of adjustment.

Fig. 7 represents a plan view of the flag holder illustrated in Fig. 3 shown detached.

Fig. 8 represents a front elevation of Fig. 7.

Fig. 9 represents, on a slightly enlarged scale, a plan view of one of the flag holders shown carried by the pull-down support in Fig. 1.

Fig. 10 represents a front elevation of a modified form of flag holder adapted to be mounted independently of a light standard, or telephone pole, or the like.

Fig. 10A represents a plan view of Fig. 10.

Fig. 11 is a fragmentary plan view of a modified form of construction.

Fig. 12 is a front elevation of Fig. 11.

Referring to the drawings in which like reference characters represent like parts, 1 designates a collar or other annular member which comprises a vertical wall having the slots 3 and 5 having its upper and lower edges deflected to form the lips 4 for reinforcement purposes. The slots 3 serve to ventilate the construction and thus reduce the hazard of rust and also serve to lighten and decorate the construction and permit of extensive adjustment of the annular member 1 to whatever size standard. In order to clamp the collar 1 about a standard (not shown) the angle irons 6 are inserted from within the collar 1 outwardly through any registering slots 3, the projecting ends of the angle irons 6 being provided with apertures through which is passed the tie-bolt 7 which is preferably curved slightly according to the curvature of the standard to which the collar 1 is applied. About the periphery of the collar 1 I mount a plurality of individual flagpole holders 8 which are best illustrated in Figs. 1, 2 and 3. By reference to Fig. 3 it will be seen that the flag holders 8 comprise the substantially cylindrical socket 10 and the arms 12, the latter terminating in the locking tabs 14 which are inserted through the appropriate slots 3 in the collar 1 and then deflected towards each other as best seen in Figs. 1, and 3. In this way each of the flagpole holders 8 is detachably but nevertheless firmly secured to the collar 1, and it will be noticed that when the collar 1 is applied to a light standard or the like, the inwardly deflected locking tabs 14 of the holders 8 are automatically clamped tight against the light standard thus making it impossible to remove the flagpole holder 8 without breaking it, unless and until the collar 1 has been removed from the light standard or other support. The locking tabs 14 are preferably punched out of the body of the holder 8 as best seen in Fig. 8, it being understood that the top edges of the holders 8 are also preferably deflected as at 16 for reinforcing purposes, the deflected ends 16 being continued from the vertical edges of the holders 45 and overlapping the upper part of the cylindrical socket 10 which supports the flagpole 18 thus greatly reinforcing the construction. The arms 12 of the holders 8 are secured together by the tie-bolt 20 which is engaged by a nut 24 bearing 50 against the adjacent wall of the holder to prevent turning while the ball 20 is being turned.

In order to effect adjustment and more effectively to clamp the cylindrical socket 10 around a flagpole 18 I provide the adjustment bolt 26. 55

The adjustment bolt 26 also loosely carries the cog wheel 30 which slightly projects into the cylindrical socket 10 as best seen in Figs. 3 and 7, the purpose of the cog wheel 30 being to engage or bite into the flagpole 18 as the latter is inserted in the cylindrical socket 10 thus further tightening the engagement of the flagpole with the holder 8 and insuring against the turning of the flagpole in the socket 10. If desired I provide the socket 10 in the holder 8 with the cut outs 32 which leave partially detached segments 34 therebetween so that, if it is found necessary to use the holder to support a pole 18, which is so small as to be beyond the range of adjustment available including the cog wheel, it will be possible to hold such a relatively small pole in position by denting the sections 34 inwardly by a hammer blow or the like as illustrated at 36 in Fig. 3, thereby reducing the diameter of the socket 10. To a flagpole 18 supported in any one of the holders 8, carried by the collar 1, I secure one of the brackets best illustrated in Fig. 9 which consists of the wall 38, having the apertures 40, 41 and extending to form the spring arms 42 the ends of which are deflected as at 44 to hold the pole 18, the arms 42 being tightened by the bolt and nut arrangement 46. The apertures 40 in the holders shown in Fig. 9 register with the corresponding apertures 48 in the body 50 of the pull-down support (see Fig. 5) while the apertures 41 are adapted to register with any corresponding pair of apertures 52. In order to secure the holder shown in Fig. 9 to the pull-down 50 a central bolt 54 is passed through any corresponding pair of the apertures 41 and 52. In this way extensive angular adjustment of the holder with respect to the pull-down support 50 may be achieved. It will be seen that on the pull-down support 50 I mount any desired number of the holders shown in Fig. 9 for supporting a plurality of additional flagpoles. The upper edge of the pull-down support 50 is deflected upon itself to form a reinforcing head 60 and is provided with apertures 62 which will engage corresponding apertures in the appropriate edge of a flag to be suspended from the upper edge of the pull-down support 50. For added stability the lower edge of the pull-down 54 may be deflected as at 63.

In Fig. 10 I have shown a modified form of flag holder for use in homes and small establishments where only one flag is to be supported at the time, and the same consists of two sections 66 and 68, the edges of which are deflected as at 69 for reinforcement and are provided with apertures 70 through which screws or bolts or nails can be driven into a wall, door, or other support. The sections 66 and 68 are provided with complementary jaws 72 and 74 which are clamped together about a pole (not shown) by one or more bolts 76. The jaws 72 and 74 may be round to form a round socket, or may be angularly deflected as shown in Fig. 10 to form a polygonal socket.

In Figs. 11 and 12 I have illustrated a modified form of the construction shown in Fig. 1 in which, instead of the collar 1 which is in the form of a flat band of a certain width, I construct the annular member, which engages the light standard, out of wire sections 80 which are of any desired length and which are suitably curved or capable of being bent to a curve to correspond to the curvature of the light standard. Each of the wire sections 80 is provided with the deflected ends 82 which are adapted to

engage apertures 84 in the flanges of a flagpole holder 90 which is similar to the holder shown in Figs. 7 and 8 except that the locking tabs 14 are omitted since the holder 90 is fastened as at 82. The slots 32 shown in Fig. 8 may be used in or omitted from the holder 90. The holder 90 is also provided with the adjustment bolt 20, the bolt 16 and the cog wheel 30. The other ends of the wire sections 80 are deflected to form eyes 100 which engage the slightly curved tie-bolts 102. In the socket of the holder 90 a flagpole 18 may be positioned to support a flag, and, if desired, the pull-down construction illustrated in Fig. 1 can be supported from such flagpole in the exact manner above explained. It will be noted that the deflected ends 82 of the wire sections 80 lie flat against the flanges 86 of the flag holder, and that, when the collar formed of the wire sections is clamped around a light standard, the deflected ends 82 are pressed against the standard thus preventing withdrawal thereof. The wire sections 80 may be made of different lengths and thicknesses and can be manufactured in standard sizes from which any desired size of collar can be built up by simply using a greater or lesser number of wire sections. This construction is cheaper and lighter, and the parts can be carried in disassembled or knock-down compact condition.

Having thus described my invention, what I claim as new and desire to secure by Letters Patent is:

1. In a device of the character stated, a collar, fastening means for adjustably clamping said collar around a pole, there being spaced slots in the body of said collar for adjustable engagement with said fastening means, and a flagpole supporting bracket adapted to be carried by said collar and comprising a socket for receiving the pole of a flag, said socket merging into a pair of spring arms, and tabs at the ends of said spring arms adapted to pass through said slots and to be deflected against the inner face thereof.

2. In a device of the character stated, a collar, fastening means for adjustably clamping said collar around a pole, there being spaced vertical slots in the body of said collar for adjustable engagement with said fastening means, and a flagpole supporting bracket adapted to be carried by said collar and comprising a socket for receiving the pole of a flag, means for tightening or relaxing said socket, said socket merging into a pair of spring arms, and tabs at the ends of said spring arms adapted to pass through said slots and to be deflected against the inner face thereof.

3. In a device of the character stated, a collar, fastening means for adjustably clamping said collar around a pole, there being spaced vertical slots in the body of said collar for adjustable engagement with said fastening means, and a flagpole supporting bracket adapted to be carried by said collar and comprising a socket for receiving the pole of a flag, a toothed member projecting into said socket and adapted to engage a pole inserted therein, said socket merging into a pair of spring arms, and tabs at the ends of said spring arms adapted to pass through said slots and to be deflected against the inner face thereof for securing said bracket to said collar.

4. In a device of the character stated, a collar, fastening means for adjustably clamping said collar around a pole, there being spaced vertical slots in the body of said collar for adjustable engagement with said fastening means, and a

flagpole supporting bracket adapted to be carried by said collar and comprising a socket for receiving the pole of a flag, a rotary toothed member projecting into said socket and adapted to engage a pole inserted therein, said socket merging into a pair of spring arms, and tabs at the ends of said spring arms adapted to pass through said slots and to be deflected against the inner face thereof.

5. In a device of the character stated, a collar adapted to be adjustably secured to a light standard or the like, and a flag holder carried by said collar, comprising a socket for receiving the pole of a flag and a rotary toothed element carried by said bracket and projecting into said socket for engaging said pole.

WILLIAM F. HOGAN.
